UNITED STATES PATENT OFFICE.

GROVER C. SEYMOUR, OF GLEN RIDGE, NEW JERSEY.

RECEPTACLE CLOSURE.

Application filed February 20, 1922. Serial No. 537,814.

To all whom it may concern:

Be it known that I, GROVER C. SEYMOUR, a citizen of the United States, residing in Glen Ridge, county of Essex, State of New Jersey, have invented certain new and useful Improvements in Receptacle Closures, of which the following is a specification.

My invention relates to receptacle closures and is particularly, altho not exclusively, useful in connection with closures for cans and collapsible tubes for containing toilet preparations such as tooth powder and paste, soap, greases, etc.

The general object of my invention is to provide a new and improved closure which is simple in construction and cheap to manufacture, and which is readily movable from its closed to its open position and vice versa.

My invention will be understood from the following description taken in connection with the accompanying drawing in which Figure 1 is a side elevation of a receptacle having the invention applied thereto, the cap being in its closed position; Figure 2 is a side elevation of the upper part of the receptacle shown in Figure 1, but with the cap in its open position; Figure 3 is a fragmentary top view, on an enlarged scale, of said receptacle with the cap in its open position; Figure 4 is an elevation, also on an enlarged scale, of the upper portion of said receptacle taken at a right angle to Figure 1, with the cap in its closed position; Figure 5 is a fragmentary elevation partly in section of the neck of the receptacle with which the cap co-operates; Figure 6 is a fragmentary sectional elevation thru the neck of the container with the cap applied thereto; and Figure 7 is a sectional elevation of a cap embodying my invention provided with a spur for puncturing the sealed opening of a container to which it is applied.

Referring to the drawing, the body of the receptacle 10 is shown as provided with a conical top 11 from which projects a neck 12 provided with an opening thru which the contents of the receptacle may be ejected. The cylindrical surface of the neck 12 is provided with one or a plurality of notches 14 of the form best shown in Figures 5 and 6, from which it will be noted that while the notch has an abruptly curved bottom portion its upper portion slopes gradually from the curved edge of the top of the neck 12. Arranged for co-operation with the

neck 12 and for covering the opening therein, is a cap 17 of the form clearly shown in the drawing. This cap is provided with one or a plurality of slots 19 thru which 60 extends a spring retaining member 20 adapted to enter the notches 14 and hold the cap 17 in the position in which it closes the opening thru the neck 12. The spring retaining member 20 may be of any suitable 65 form, and preferably also serves as a pivotal support for the cap 17 on the receptacle 10. In the construction shown, the spring retaining member 20 surrounds the cap 17 and is provided with straightened portions 70 22 which enter the slots 19, the ends 23 of the spring retaining member being bent as shown and arranged to make pivotal connection with perforated lugs 24 preferably formed integral with and extending upwardly from the conical top 11 of the container. When the cap is in its open position, the spring retaining member is in the position shown in Figure 3 from which it will be evident that the straightened sides 75 22 of said retaining member lie within the slots 19 and extend into the space within the cap 17. When the cap is moved into engagement with the neck 12, the rounded edges 15 of the neck engage the straightened portions 22 of the spring retaining member, and the latter is sprung outwardly to permit the cap to be forced to its closing position in which the straightened portions 22 of the spring member as 80 assume the positions in the notches 14 best shown in Figure 6. During this closing movement, after the spring member has moved downwardly over the rounded edges 15 of the neck 12, the spring member by its 85 engagement with the surfaces leading to the notches 14 tends to draw the cap 17 to its seated position and yieldingly hold it there. This is conducive to maintaining a tight 90 seal between the top of the neck 12 and the 100 inside of the top of cap 17.

In Figure 7 the cap 17' is shown as provided with a spur 26 which may serve in a well known manner to puncture a seal in the outer end of the neck 12 which may be 105 provided at that location for hermetically closing the container 10 prior to use of the contents thereof. As is customary, a piece of cardboard may be inserted between the top of the neck 12 and the spur 26 to prevent premature puncturing of the seal during 110 shipment and handling of the container.

2
While I have shown certain constructions in which my invention may be embodied, it is to be understood that it is my intention in the appended claims to cover any modifications which come within the scope thereof.

What I claim is:

1. In combination, a receptacle having a neck provided with an opening thru which the contents of the receptacle may be ejected, said neck being provided with a notch in the outside thereof, a cap adapted to co-operate with said neck and cover the opening therein, said cap having a slot in its side, and a spring retaining member extending thru said slot and entering said notch.
2. In combination, a receptacle having a neck provided with an opening thru which the contents of the receptacle may be ejected, said neck being provided with a plurality of notches in the outside thereof, a cap adapted to co-operate with said neck and cover the opening therein, said cap having a plurality of slots in its side, and a spring retaining member extending thru said slots and entering said notches.
3. In combination, a receptacle having a neck provided with an opening thru which the contents of the receptacle may be ejected, said neck being provided with oppositely located notches in the outside thereof, a cap adapted to co-operate with said neck and cover the opening therein, said cap having oppositely located slots in its side, and a spring retaining member extending thru said slots and entering said notches.
4. In combination, a receptacle having a neck provided with an opening thru which the contents of the receptacle may be ejected, said neck being provided with two oppositely located notches in the outside thereof, a cap adapted to co-operate with said neck and cover the opening therein, said cap having two oppositely located slots in its side, and a spring retaining member extending thru said slots and entering said notches.
5. In combination, a receptacle having a neck provided with an opening thru which the contents of the receptacle may be ejected, said neck being provided with a rounded edge portion and a notch below it, a cap adapted to co-operate with said neck and cover the opening therein, said cap having a slot in its side, and a spring retaining member extending thru said slot and entering said notch.
6. In combination, a receptacle having a

neck provided with an opening thru which the contents of the receptacle may be ejected, said neck being provided with a rounded edge and a plurality of notches in the outside of said neck below the rounded edge thereof, a cap adapted to co-operate with said neck and cover the opening therein, said cap having a plurality of slots in its side, and a spring retaining member extending thru said slots and entering said notches.

7. In combination, a receptacle having a neck provided with an opening thru which the contents of the receptacle may be ejected, said neck being provided with a notch in the outside thereof, a cap adapted to co-operate with said neck and cover the opening therein, said cap having a slot in its side, and a spring retaining member extending thru said slot and entering said notch and serving as a pivotal support for said cap on said receptacle.

8. In combination, a receptacle having projecting from its top perforated lugs and a neck provided with an opening thru which the contents of the receptacle may be ejected, said neck being provided with a notch in the outside thereof, a cap adapted to co-operate with said neck and cover the opening therein, said cap having a slot in its side, and a spring retaining member surrounding said cap and extending into the slot therein and making pivotal connection with said lugs.

9. In combination, a receptacle having projecting from its top perforated lugs and a neck provided with oppositely located notches in the outside thereof, a cap adapted to co-operate with said neck and cover the opening therein, said cap having oppositely located slots in its side, and a spring retaining member surrounding said cap and extending into the slots therein and making pivotal connection with said lugs.

10. In combination, a receptacle having a neck provided with an opening thru which the contents of the receptacle may be ejected, a cap adapted to co-operate with said neck and cover the opening therein, and a spring retaining member surrounding said cap and holding it in position on said neck to cover the opening in the latter and also serving as a pivotal support for said cap on said receptacle.

In testimony whereof I have affixed my signature to this specification.

GROVER C. SEYMORE.
